(57) **CLAIM**

The ornamental design for a base for an oval lighting fixture, as shown and described.

DESCRIPTION

FIG. 1 is a perspective view of my new design in its environment, namely, mounted to an oval light lens. The lens is shown in broken lines for illustrative purposes only, and forms no part of the claimed design;

FIG. 2 is a top view of the design of FIG. 1;

FIG. 3 is a bottom view of the design of FIG. 1

FIG. 4 is a side elevation view of the design of FIG. 1; and, FIG. 5 is an end elevation view of the design of FIG. 1.
